UNITED STATES PATENT OFFICE.

HARRY T. ABOLIN, OF WOOD RIDGE, NEW JERSEY, ASSIGNOR TO LINCRUSTA-WALTON COMPANY, INC., OF HACKENSACK, NEW JERSEY, A CORPORATION OF NEW JERSEY.

DESIGN FOR A WALL PAPER OR SIMILAR ARTICLE.

Application filed March 22, 1926. Serial No. 17,005. Term of patent 3½ years.

To all whom it may concern:

Be it known that I, HARRY T. ABOLIN, a citizen of the United States, residing at Wood Ridge, in the county of Bergen, State of New Jersey, have invented a new, original, and ornamental Design for a Wall Paper or Similar Article, of which the following is a specification, reference being had to the accompanying drawing, forming part thereof, in which the figure is a plan view of a piece of wall paper embodying my new design.

I claim:—

The ornamental design for a wall paper or similar article as shown.

HARRY T. ABOLIN.
